United States Patent Office

Des. 190,812
Patented July 4, 1961

190,812

ARTIFICIAL LARYNX

Robert E. Polk, Indianapolis, Ind., assignor to Bell Telephone Laboratories, Incorporated, New York, N.Y., a corporation of New York

Filed May 12, 1960, Ser. No. 60,550

Term of patent 14 years

(Cl. D26—14)

FIG. 1

FIG. 2

FIG. 3

FIG. 1 is a perspective view of an artificial larynx showing my new design;

FIG. 2 is a side elevation view, the opposite side being substantially a mirror image thereof; and

FIG. 3 is a plan view thereof.

What I claim is:

The ornamental design for an artificial larynx, as shown and described.
